UNITED STATES PATENT OFFICE

SAMUEL E. TURNER, OF WICHITA FALLS, TEXAS, ASSIGNOR TO PANHANDLE REFINING COMPANY, OF WICHITA FALLS, TEXAS

OUTLET VALVE FOR TANK CARS

Application filed January 16, 1926. Serial No. 81,799.

The present invention relates to tank cars and more particularly to outlet valves therefor.

At present, all tank cars are provided with a discharge pipe or outlet leg riveted to the bottom of the tank by a flange, the outlet leg extending downward below the shell of the tank, about eighteen inches. The usual valve provided is in the form of a plug valve inserted in the top of the outlet leg from the inside of the tank car, and having a core or guide about six inches long extending down into the outlet leg. The upper part of the plug carries an annular shoulder forming the movable valve member element which is seated on the upper rim of the outlet leg. The top of the valve core is provided with a rectangular socket member in which is fitted an operating rod held in the socket by a transverse pin or bolt and extending upwardly through the tank into the dome where it is supported in a suitable valve rod support. The valve is held down on its seat under spring tension and operated by a cam lever arranged to pull on the rod against the tension of the spring. The disadvantages of this usual type of valve are: that the core or guide extends down so far into the outlet leg that in case of a wreck or other case which might result in the breaking off of the outlet leg near the shell of the tank, the valve would be unseated or injured with resultant loss of the contents of the car; as the valve is held closed only by downward pressure of a spring, it is liable to become unseated in heavy switching and theft of contents may be easily accomplished by exerting upward pressure on the valve either through the valve stem or on the valve plug direct from beneath the car without breaking the seal; because of its being a poppet valve type with small seating area and raising off its seat to permit discharge over the valve seat surface, this surface is exposed to the contents of the car and to the atmosphere and gases when the car is empty resulting in corrosion and pitting of the valve seat; the lifting of the valve off its seat in discharging permits any foreign substance or objects that may be in the tank to

become lodged between the valve and its seat preventing it from closing.

It is the object of the present invention to overcome these disadvantages by the provision of an improved valve, valve support, and outlet leg structure so constructed in relation to each other and to the car as to insure against breakage or disarrangement of the valve during ordinary or unusually rough usage of the car or upon bending or breaking off of the outlet leg, and to arrange the operating parts so that the valve will be substantially proof against unauthorized operation, and the valve seat protected from the corrosive action of the car contents and the atmosphere or other gases.

Other objects and various novel and advantageous features of the present invention will be apparent from a perusal of the following specification and the drawings accompanying the same.

In the drawings:

Fig. 1 is a detail view of the valve per se, partly in section;

Fig. 2 is a sectional view taken on the line 2-2 of Fig. 1;

Fig. 3 is an assembly view on a reduced scale, taken on a transverse cross section through the tank of a tank car, the tank being shown fragmentarily.

Referring to the drawings in detail, 1 is the valve cage having a bore 2 forming the stationary valve seat in which is fitted a cooperating valve core 3 carried by the movable valve member 4. The outer surface of the core 3 and the engaging surface of the bore 2 are given a slight downward taper and ground to fit. A downwardly opening recess 5 is formed in the core with a pair of side openings or ports 6 arranged to be brought into register with a pair of similar ports 7 in the valve cage 1. Close to the level of the bottom of the ports 7 are water drain openings or ports 8 in the core 3 spaced slightly to one side of each port 6 where they may be moved into communication with the ports 7 without permitting communication between ports 6 and 7. The lower end or bottom of the valve cage 1 is threaded at 9 for engagement with the internally threaded portion 10 at the

upper end of an outlet pipe or leg 11 secured over an opening 12 in the bottom of the tank 13 by a flange 14 and rivets 15. In connecting the cage and outlet leg 11 the threaded engagement is set sufficiently tight to produce a substantially fixed joint whereby the valve cage is held fixed in relation to the tank through the fixed connection of the leg 11. In the top portion of the movable valve member 4 is provided a socket member 16 having a rectangular socket 17 in which is fitted the flat rectangular end 18 of a valve turning or operating shaft 19 held in the socket by a locking pin 20 passed through the transverse pin openings 21 in the socket member and a hole (not shown) in the flattened end of the shaft 19. The shaft 19 extends upwardly into the dome 22 where it passes through and has bearing in the supporting bracket 23, the shaft is provided with an operating hand wheel 24 fixed thereon and carrying a downwardly extending leg 25 on which is slidably mounted a latching bolt 26 arranged to drop into an opening in the bracket 23 to latch the wheel and valve in closed position, the bolt 26 being provided with a thumb lever 27 for raising the same. Another leg 28 is carried by the hand wheel 24 and extends down through the plane of the bracket 23 so that its path of travel will be intercepted by the bracket and thus operate as a stop for limiting the angular movement of the valve as predetermined by the setting or spacing of the leg 28 with respect to the other parts. Either of the legs 25 or 28 may be provided with an opening as indicated at 29 through which, and a hole suitably located in the bracket 23, a car seal wire may be passed for sealing the valve in closed position. To prevent upward movement or unseating of the valve, a stop collar 30 is fixed on the valve shaft 19 close to the bottom of the supporting bracket 23 but spaced just sufficiently there-below to allow for unequal expansion and contraction of the tank and valve shaft. To prevent the outlet leg 11 from being bent so far out of line or breaking off so close to the bottom of the tank as to endanger the valve structure, the outlet leg is made relatively weaker at a point safely below the tank by an annular groove as indicated at 31. Corrosion of the valve members 1 and 4 is prevented by making them of non-corrodible metal such as Hills-McCanna alloy, and it is to be noted that as such metals are usually softer than steel their use is made practicable in a valve to be used for the purpose described, only by a structure of the type disclosed where the wearing surfaces are large and protected against concussion or pounding and the lodgment of foreign matter between the valve and its seat.

It will be seen from the angular relation of the dotted line radii a in Fig. 2, which pass through the remote edges of ports 7 and 8, re-

spectively, that in operation a quarter turn of the valve core in a counter clockwise direction will effect a complete closure of the valve, while after closure a slight clockwise turn will bring the water drain ports 8 into communication with the ports 7 and enable water or other sediment to be slowly and carefully drained off without substantial loss of useful contents.

What I claim is:

1. A tank car outlet valve structure comprising an outlet leg fixedly secured to the bottom of the tank, a valve cage mounted in the top of the outlet leg within the tank having a vertical bore therein in communication with the outlet leg and cage ports connecting the interior of the bore with the interior of the tank, a vertical valve core fitted in said bore and having a chamber opening downwardly in communication with the outlet leg and provided with main ports arranged to be rotated into register with the cage ports, said valve core being provided with a water drain port arranged to be opened independently of the said main ports, an operating shaft for the valve core extending into the dome of the tank, a support for the shaft mounted in the dome, and operating means connected with the shaft in the dome.

2. In a tank car having a downwardly extending outlet leg, a rotary valve structure mounted at the top of the outlet leg substantially wholly within the tank and means within the tank for operating said valve structure to open and close a channel from the car into the outlet leg, together with a drain port in said valve independent of the main channel, said drain port being arranged with its lowermost level at the lowermost level of the tank.

3. In a tank car having an outlet opening in the bottom or lowermost level of the tank, the combination of a valve cage mounted over the opening and having a cage port arranged with its lower edge at substantially the lowermost level of the tank, a variable valve member in the cage having a main valving port arranged to connect said cage port with the said outlet and a drain valving port smaller than said main port or the cage port arranged to connect the cage port with the said outlet independently of the main port, said drain port being arranged with its lowermost level at the lowermost level of the cage port.

4. A valve for tank cars comprising a cage having a main port, adapted when open to connect the interior of the tank with an outlet, a variable valve member in the cage having a main valve port arranged to connect said cage port with the said outlet and a drain valve port in said valve member smaller than said main port or the cage port, the angular relation of said ports in said variable valve member being such that in operation approximately a quarter turn of the valve in one direction will effect a complete closure of

- the valve, while a slight turn in the other direction will bring the drain port into communication with the cage port and enable water or other sediment to be drained off without substantial loss of useful contents. 5. An outlet valve for tank cars comprising the following instrumentalities: an outlet leg flanged at its upper end and the flange secured to the bottom tank sheet of the car, a 10 valve cage secured into the upper end of the bore of said outlet leg, and an inverted cup-shaped valve core, said cage being open through its bore from top to bottom and provided with lateral ports above the level of the 15 flange on the outlet leg, and said cup-shaped core dropped into the cage with its open end down and its closed end up and carrying an annular horizontal flange extending outwardly around its closed end to cover and protect the bearing surfaces of cage and valve, with lateral ports in the lower walls of the core cooperating with the ports in the cage, so that when dropped into the cage the core forms therewith a two-part valve with the 20 top closed, the bottom open and only lateral inlet ports or openings. 6. The two-part valve claimed in claim 5, in which the cage has thick walls and heavy mass and the core also has heavy mass to normally maintain itself in position in the cage, the combined masses having a natural period of vibration below that of any of the adjacent parts of the car. 7. The two-part valve claimed in claim 5, in which the cage and the core combined have a heavy mass with a natural period of vibration lower than that of the adjacent parts of the car, the mass of the core being sufficient to maintain it in position within the cage 40 under all conditions, except those of malicious tampering, with means extending into the dome of the tank for turning said core and other means associated therewith outside the valve acting as a limit stop to prevent vertical 45 lifting of the core in or out of the cage. 8. A two-part valve for tank cars comprising the following instrumentalities: an outlet leg flanged at its upper end and having the flange riveted to the bottom tank sheet of the 50 car around an opening in the tank sheet sufficient to leave clearance around the opening through the outlet leg, a valve cage of heavy mass with an opening extending through it and slightly tapering inward from top to 55 bottom, said cage having its lower end threaded to the upper end of the outlet leg, lateral ports in the side walls of said cage just above the level of the top of the flange of the outlet leg, and a valve core also of heavy mass in the 60 shape of an inverted cup closed at its top and open at its lower end externally tapered to fit the cage and provided with a horizontal flange extending outwardly around its closed end and adapted when the core is in position to 65 completely cover and protect the bearing be- 70 75 80 85 90 95 100 105 110 115 120 125 130
- tween the core and cage, said core provided with a socket in its upper or closed end to receive the lower end of an operating rod, the upper end of said rod extending into the dome of said tank and there provided with means to prevent vertical or rotary movement thereof, whereby its low natural period of vibration and the action of gravitation will tend to keep the valve seated under all conditions except those of malicious tampering, and the operating rod will prevent displacement by such tampering.
- In testimony whereof I hereunto affix my signature.
- SAMUEL E. TURNER.
